UNITED STATES PATENT OFFICE.

WILLIAM H. CUNNINGHAM AND JAMES T. ROWAN, OF PITTSFIELD, MASSACHUSETTS.

WATER-COOLED GRATE.

Application filed January 12, 1926. Serial No. 80,849.

This invention relates to stove grate structures and pertains particularly to a water cooled grate.

The primary object of this invention is the provision, in a manner as hereinafter set forth, of a grate structure for stoves having water passages therethrough whereby water may be caused to pass through the grate for heating purposes and carried to a storage tank of the type usually used in connection with stoves and furnaces, the structure being especially designed to provide means for supplying hot water at all times and at the same time do away with the usual water back box which is located in stove and furnace fire boxes.

The invention has for another object the provision of a grate structure having tubular bars upon which the grate dogs are supported and through which water is adapted to flow to prevent any possibility of the burning out or buckling of the grate structure as sometimes happens when ashes are allowed to back up against the grate from the underside.

A still further object of the invention is the provision, in a manner as hereinafter set forth, of a grate structure formed of a plurality of intermeshing removable dogs of substantially triangular conformation and designed when properly arranged to present a flat grate surface for the support of coal and ashes, the said dogs being loosely interlocked to prevent any binding or buckling upon expansion or contraction of the parts.

A final object of the invention is the provision, in a manner as hereinafter set forth, of a water cooled separable gear operated grate structure which is of simple but strong and durable construction, easily and quickly installed, adapted to have parts replaced as desired, and inexpensive to manufacture and set up.

The invention will be best understood from a consideration of the following detailed description taken in connection with the accompanying drawings forming a part of this specification, with the understanding that the invention is not confined to any strict conformity with the showing of the drawings but may be changed and modified so long as such changes and modifications mark no material departure from the salient features of the invention as expressed in the appended claim.

In the drawings:

Figure 1 shows the grate embodying this invention in top plan view and in position in a fire box, a portion of the front of a stove structure being shown in horizontal section. 60

Figure 2 shows in front elevation the fire box housing the grate showing the meshed operating gears mounted upon the outer end of the firebox.

Figure 3 is a longitudinal section taken 65 upon the line 3—3 of Figure 1.

Figure 4 is a transverse section taken upon the line 4—4 of Figure 1.

Figure 5 is a transverse section taken upon the line 5—5 of Figure 1. 70

Figure 6 is a horizontal section taken upon the line 6—6 of one of the dogs shown in Figure 5, the dog being removed from the grate structure.

Figure 7 is a vertical longitudinal section 75 taken through the dog shown in Figure 6, upon the line 7—7 of this figure.

Referring now to the drawings in detail wherein like numerals of reference indicate corresponding parts throughout the several views, the numerals 1 and 2 indicate a portion of the front and back respectively of a stove or furnace structure. Figure 3 indicates the side walls of the same and mounted within the lower part of the furnace structure between the front and back and side walls thereof, is the firebox base portion indicated as a whole by the numeral 4, which is supported upon proper flange supporting structures 5' located in the ash pit of the 80 stove. 85

The firebox base 4 which is removable from the lower portion of the stove structure is provided with the longitudinally extending spaced parallel tubular bars or pipes 5, the ends of which extend through the end walls of the base structure 4 as shown. The rear ends of the tubular bars 5 are provided with screw threads as indicated at 6 to enable these tubes to be connected to a water tank, while the forward ends of the bars which extend through and beyond the front wall of the base 4 are connected by means of the return tube 7 so that water flowing in at the rear end of one of the bars will pass through the return tube and out of the adjacent bar. As shown in Figures 1 and 3, the front wall of the firebox base portion 4 is spaced a substantial distance from the front wall 1 of the stove structure, to enable 105 110

the return tube 7 to be housed between these two walls.

Mounted upon the forward end of each of the tubular bars 5 in front of the front wall 5 of the base 4, is a gear member 8 and, as shown in Figure 2, these gears are in mesh so that upon the turning of one, the other one will turn also.

Each of these gears 8 has a hub 9 which 10 extends inwardly therefrom and through the front wall of the base of the firebox 4. As is shown, each of these hubs is provided with a central transverse slot 10, the purpose of which will become apparent as the description proceeds. These hubs bear directly upon the base 4 through which they extend.

Mounted upon each of the tubular bars 5 is a plurality of equilateral triangular dogs 11, each of which has a central opening 20 therethrough, through which the bar extends. Each of these dogs 11 is provided with a tubular extension or hub portion 12, one end of which is formed to provide the centrally positioned transverse tongue or diametrically oppositely positioned tongue sections 13, while the other end of the hub is provided with the diametrically positioned aligned slots 14, as shown in Figures 6 and 7. This construction of the dogs is the same 30 for all except those dogs 15 which are positioned at the rear ends of the tubular bars 5 and these dogs while provided at one end of the hub 16 with the tongues 17 are not provided at the other end of the hub with 35 the slots like those with which the hubs of the dogs 11 are provided.

These unslotted ends of the hubs 16 of the end dogs 15, bear against the rear wall of the firebox base 4 as shown in Figures 40 1 and 3. The hubs 16 axially align with the central openings of the dogs 11.

As is clearly shown in Figures 1 and 3 the forward one of the dogs 11 upon each of the bars 5 has the tongue portions 13 engaged in the slots 10 of the hubs 9 of the adjacent gear members 8 and each of the succeeding dogs upon these tubular bars has the tongue portions of the hubs engaged in the slot or slots formed in the end of the hub of the preceding dog. In this manner all of the dogs are held in radially intermeshed or interlocked revoluble relation upon the tubular bars 5 and upon the turning of the gears 8, the dogs can be made 55 to revolve or oscillate upon the bars.

As is clearly shown in Figures 1 and 3 the tongues and slotted parts of the hubs of the dogs are not tightly fitted together but are slightly spaced apart. This is to 60 allow for the longitudinal expansion and contraction of the dogs upon the tubular bars 5 to prevent any binding or buckling of the same through the action of the heat.

The front and rear walls of the firebox 65 base portion 4 may be provided with

tongued removable sections which will enable the assembler to set the tubular grate bars in position with the dogs mounted thereon after which the removable sections, indicated by the numeral 18, may be replaced to hold the tubular bars 5 in position.

In order to shake the grate structure embodying this invention, there is provided a crank 19 having the elongated right angled shaft 20, upon and adjacent the outer 75 end of which there is mounted a pinion gear 21, which is adapted to mesh with one of the gears 8 to cause the same to be revolved or oscillated upon proper movement of the crank 19. The free end of the shaft 20 is 80 adapted to have bearings in the front wall of the base 4 as indicated at 22, and the shaft adjacent its inner end is provided with a collar member 23 for the purpose about to be described.

The front wall 1 of the stove body is provided with a relatively large opening in which the collar 23 carried upon the shaft 20 of the crank is adapted to fit, when the crank is in the position shown in Figure 1. 90 When the crank is removed from this position to disengage the pinion gear 21 from the gears 8, a wicket 24, which is pivotally mounted as at 25 upon the front wall 1, may be swung down over the opening which 95 the collar 23 fits to close the same and thus prevent any dust from leaving the ash pit of the stove.

Having thus described our invention what 100 we claim is:—

In a furnace grate structure a plurality of spaced, stationary, parallel tubes constituting water heating conduits extending through the fire box of the furnace and having a communicating connection therebetween at their front ends positioned forwardly of the fire box of the furnace, a shiftable set of grate dogs mounted on each tube within the fire box, each dog of a set consisting of an inverted equilateral triangular shaped body portion having an axial opening for the passage of a tube and further including oppositely extending tubular extensions axially aligning with the opening thereof, said extensions having means providing radial intermeshing connections between adjacent dogs, meshed gears mounted upon the tubes outside of said fire box and each including a hub extended inwardly through the front fire box wall and provided with means for engaging the forward intermeshing connection of the tubular extension of the adjacent dog, and means for oscillating one of said gears whereby to operate the sets of grate dogs.

In testimony whereof, we affix our signatures hereto.

WILLIAM H. CUNNINGHAM.
JAMES T. ROWAN.
